(57) **CLAIM**

The ornamental design for a blast chiller, as shown and described.

DESCRIPTION

FIG. 1 is an isometric view from a first, side perspective of a blast chiller;

FIG. 2 is a first side view thereof;

FIG. 3 is a second side view thereof;

FIG. 4 is a third side view thereof;

FIG. 5 is a fourth side view thereof;

FIG. 6 is a top side view thereof; and,

FIG. 7 is a bottom side view thereof.

Broken lines are also for illustrative purposes only and form no part of the claimed design.
